UNITED STATES PATENT OFFICE.

CHARLES E. EGAN, OF PETERSBURG, ILLINOIS, ASSIGNOR, BY DIRECT AND MESNE ASSIGNMENTS, TO EGAN ELECTRIC MASSAGE VIBRATOR COMPANY.

MASSAGE APPARATUS.

No. 879,041.

Specification of Letters Patent.

Patented Feb. 11, 1908.

Application filed January 26, 1906. Serial No. 297,973.

To all whom it may concern:

Be it known that I, CHARLES E. EGAN, a citizen of the United States, residing at Petersburg, in the county of Menard and State of Illinois, have invented a certain new and useful Improvement in Massage Apparatus, of which the following is a specification, reference being had therein to the accompanying drawings.

10 This invention relates to massage apparatus, and particularly to such as is actuated by electrically-driven motor means. Heretofore such means have been of necessity unwieldy and difficult to move about, also of a 15 size and shape that would prevent their ready manipulation, even without regard to their mass. In a few instances where such motor means have been applied to massage purposes, it has been necessary to move the 20 body to be treated into operative position with regard to the massage apparatus, or to provide a flexible shaft or coupling which would permit the driven apparatus to be moved with regard to the motor. Both of 25 these arrangements have proved more or less unsatisfactory, except in a limited class of work, and for many purposes where massage would otherwise be applied, it has been barred by the nature of the only devices available.

30 It is the object of my present invention to produce a massage apparatus which can be supplied from any convenient source of electrical current, which will be light and easy to manipulate, which will not necessitate any expensive or elaborate fittings or 35 connections, and which will operate with a maximum efficiency and a minimum of inconvenience to the person treated.

In order to attain the object of my invention I have selected a vibrating electrical motor as the most suitable for my purpose, of the same general type as those employed in electrical bells, making such changes in this motor as are necessary to adapt it particularly to my purpose. I provide this with a massage head of suitable form and construction, and arrange the parts so that the circuit of the motor magnet is normally broken, and the device automatically rendered inactive until it is taken up for use. I inclose the entire apparatus in a small compact box, with a handle so arranged relatively to the massage head that the degree of pres-

sure applied in certain directions will determine the amount of energy expended in 55 the vibration.

The magnets of my motor are suitably wound to take current either from a commercial source, such as an electric lighting circuit, or from a primary battery which 60 may be carried in a portable case. The device is thus available in any locality, and without undue expense.

The invention is illustrated in the accompanying drawings, in which—

65 Figure 1 is a side elevation, and Fig. 2 is a central section thereof.

Referring to the drawings, 1 represents a manipulating handle which is secured by a screw-threaded stud 3 and a casing 2 adapted to inclose the working parts of the apparatus. This stud 3 and the handle 1 are both provided throughout their length with a channel or opening for the reception of the circuit wires 4, which are led out from the end of the handle to the connecting terminals, for attachment to electric light circuit or battery, as is deemed advisable, or as expediency requires.

70 Mounted on a suitable base 5 secured within the casing are the magnets 6, which are mounted side by side, as in electric bell constructions, and which are provided with the usual soft iron cores 7, in this instance; and provided with non-magnetic contact points 8, with which the armature 9 contacts, so as to prevent it from sticking. Adjacent the magnets 6, and also mounted upon the base 5, is an upright or post 10, to which is secured the flat spring 11 of the armature 9. This flat spring 11 connects the armature to the post 10, and normally holds the armature in engagement with the non-magnetic contacts 8. To the top of the armature is secured the contact spring 12, which is normally out of 85 engagement, but adapted to contact, with a platinum point on a frame 13, which extends up from the side of one magnet 6, and overhangs the core of said magnet and the armature 9.

100 The outer end of the armature 9 is enlarged as at 14, to accommodate the screw 15 for attaching the rubber cup 16, which is provided in this instance with a serrated or toothed edge 17. This cup is secured between two washers 18 and 19, and a clamp

nut 20 is provided so that the structure comprising the cup 16, the washers 18 and 19, the screw 15, and the nut 20, may be removed as a whole from the end of the armature and replaced by different shaped cups to be used upon different parts of the body as the operator desires. The screw 15 projects through and beyond the nut 20, and is threaded with-in the enlarged portion of the armature 14.

10 The circuit through the device is as follows: From battery or electric light circuit, (and in this latter instance the windings of the magnets would have to have a somewhat greater resistance), through the handle 1 and the stud 3 to the magnets 6, to the frame 13, and when the armature is closed, through the armature 9, flat spring 11, post 10, and to battery or electric light circuit through handle 1.

15 20 The operation is as follows: The circuit normally being broken by the armature resting upon the core, instead of the contact spring 12, being in engagement with the frame 13, so as to normally have the circuit closed, as in electro-vibrating bells, it is necessary that the cup 16 be placed against some object or some part of the body, and raised so as to bring the spring 12 into contact with the frame 13. This completes the 25 circuit and starts the vibration of the armature, which will continue as long as the device is pulled in a direction so as to force the armature and the contact springs 12 into engagement with the frame 13, so as to complete the circuit.

30 35 Having thus described my invention, what

I claim and desire to secure by Letters Patent is—

In an electric massage vibrator, the combination with an inclosing casing, of a base therein, electromagnets mounted upon said base, a post projecting up from said base adjacent said electromagnets and in line therewith, an armature pivoted at one end to the post and overlying the electromagnet, a massaging device interchangeably connected to one end of the armature, a spring at the opposite end of the armature adapted to hold it against the cores of said electromagnets, a frame overhanging the armature above the core of one of the electromagnets, a contact on said frame, a contact spring carried by said armature adapted to engage the contact of the frame but normally held away from the contact by the resilience of the spring which holds the armature against the cores of the electromagnets, said contact spring adapted to engage the contact on the frame upon operation of the massage device so as to complete the circuit of the electromagnet and start vibration of the armature, an operating handle attached to the casing at right angles to the armature and parallel to the axes of the magnets, and a channel running through said operating handle adapted to receive the circuit wires of said electromagnet.

In testimony whereof I affix my signature in presence of two witnesses.

CHARLES E. EGAN.
